UNITED STATES PATENT OFFICE.

HENRY KEY MILNER, OF BIRMINGHAM, ALABAMA.

AUTOMATIC FIRE-EXTINGUISHER.

SPECIFICATION forming part of Letters Patent No. 691,283, dated January 14, 1902.

Application filed June 12, 1901. Serial No. 64,287. (No model.)

To all whom it may concern:

Be it known that I, HENRY KEY MILNER, a citizen of the United States of America, residing at Birmingham, in the county of Jefferson and State of Alabama, have invented 5 certain new and useful Improvements in Automatic Fire-Extinguishers, of which the following is a specification.

My invention relates to an improvement in 10 automatic fire-extinguishers, and while applicable to any building where the use of an extinguisher of this character is desirable it is more particularly adapted for use with dry kilns, and I have shown it applied in that connection; and the invention consists in certain 15 novel features of construction and combinations of parts, which will be hereinafter described, and pointed out in the claims.

In the accompanying drawings, Figure 1 20 is a view in longitudinal vertical section through a kiln or other chamber, the parts of the invention all being shown in side elevation; and Fig. 2 is a view in plan of the parts of the invention.

25 F represents a pipe containing the extinguishing fluid, which may be steam, water, or other fluid.

E is a controlling-valve, which normally 30 remains seated and prevents the extinguishing fluid from rising through the pipe Y above the valve and escaping through the perforated pipe Y', which latter extends throughout or approximately throughout the length of the room, chamber, or building, or kiln, 35 as the case may be, to be protected from fire. This perforated pipe may be in different forms—for instance, a straight pipe—or it is obvious that it might be in zigzag or serpentine form, or it might be provided with lateral 40 branches in order to distribute the fluid as thoroughly as possible throughout the chamber to be protected, and when applied to a dry kiln, as indicated in Fig. 1, the pipes Y and Y' are continuations or in the form of 45 a branch from the main, which supplies steam for heating the kiln. This latter is by no means a necessary construction, but for the purposes of economy is preferable.

The valve E is kept closed against the pressure of the extinguishing fluid by a long lever D, which is held normally in a vertical position, as indicated in Fig. 3, pressing the

valve against its seat. A wire C is attached to the end of the lever D, passes around vertically-disposed pulley H, thence upward over 55 vertical pulley H', then back and forth across a width of the kiln or other building around pulleys A A, thus making a network of zig-zag wiring at the ceiling of the room, and, finally, this wire passes down over the vertically-disposed pulley H''. At the free end of 60 the wire C a weight I is depended, which at all times keeps the wire C taut, thereby holding lever D in an elevated position against the valve-stem of valve E, keeping the latter 65 tightly closed. Weight I also serves a secondary purpose. It takes care of the expansion and contraction in wire C, which will be considerable, owing to the high temperature in the kiln when lumber is being dried and 70 at other times when the temperature is comparatively low, when there is no heat in the kiln. Wire C is provided at intervals with fusible links B B, or perhaps, more accurately speaking, the wire is made up of sections, the adjacent ends of which are connected together by these fusible links to form 75 a continuous wire.

At some convenient point, preferably at 80 the upper end of pipe Y, a whistle K is located, this being blown by the extinguishing fluid when valve E is opened, whereby to give a warning signal to an attendant or any one interested in the kiln or building.

In addition to the parts described I propose 85 to provide an electric bell as a means for giving a signal, and this may be used in connection with the whistle just described or in lieu thereof, and the bell may be located at any convenient point outside of or remote from 90 the kiln or building to be protected. A bell-crank lever L is pivoted in position to close a circuit through the terminals M M of the bell-circuit. A wire or cord connects one end of the bell-crank lever with another bell-crank lever N inside of the kiln or building, 95 and the opposite end of lever N is connected with the weight I by means of a cord or wire O.

If at any time fire should originate in the kiln or building and melt one of the fusible 100 links, the tension on wire C will at once be relieved, and the pressure of the extinguishing fluid against the inner end of the valve E will immediately force the valve from its seat

and open an unobstructed passage for the fluid into pipe Y and thence into the perforated pipe or pipes. At the same time the pressure of this fluid will be sufficient to blow 5 the whistle if a whistle is used, and the falling of the weight I will give a sudden jerk to bell-crank lever N, and through its connection with bell-crank lever L the lower end of the latter will be swung between the electric terminals M M of the bell-circuit, thus 10 closing the latter and causing the bell to ring. In this way the fire is not only quickly extinguished, but warning is given of the impending danger to the kiln or other building, 15 so that additional means may be employed, if need be, without loss of time to extinguish the fire.

It is evident that slight changes might be resorted to in the form and arrangement of 20 the several parts described without departing from the spirit and scope of my invention, and hence I do not wish to limit myself to the exact construction herein set forth; but,

Having thus fully described my invention, 25 what I claim as new, and desire to secure by Letters Patent, is—

1. The combination with a pipe adapted to contain extinguishing fluid, a valve therein of such form and construction that it is opened 30 by the fluid-pressure against it when not otherwise hindered, a pipe leading from the valve, and a perforated discharge-pipe leading from said last-named pipe, of a lever bearing normally against the valve, a flexible connection 35 having fusible sections, said connection attached to the lever, and a weight on the connection remote from the lever for keeping the connection taut and for holding the valve closed until the connection is severed.

40 2. The combination with a pipe adapted to

contain extinguishing fluid, a valve therein of such form and construction that it is opened by the fluid-pressure against it when not otherwise hindered, a pipe leading from the valve, and a perforated discharge-pipe leading from 45 said last-named pipe, of a lever bearing normally against the valve, a flexible connection having fusible sections, said connection attached to the lever, and a weight on the connection remote from the lever for keeping the 50 connection taut and for holding the valve closed until the connection is severed, a bell, bell-circuit, terminals for said circuit, a pair of levers loosely connected together, one pivoted in position to engage the terminals, and 55 a connection extending from the other lever to the weight.

3. The combination with a pipe adapted to contain extinguishing fluid, a valve therein of such form and construction that it is opened 60 by the fluid-pressure against it when not otherwise hindered, a pipe leading from the valve, said pipe having a whistle therein adapted to be sounded when the valve is opened by the fluid which forces the valve open, and a perforated discharge-pipe leading from said last-named pipe, of a lever bearing normally 65 against the valve, a flexible connection having fusible sections, said connection attached to the lever, and a weight on the connection 70 remote from the lever for keeping the connection taut and for holding the valve closed until the connection is severed.

In testimony whereof I have signed my name to this specification in the presence of 75 two subscribing witnesses.

HENRY KEY MILNER.
